United States Patent

Des. 236,651
Patented Sept. 2, 1975

236,651

LAMP

Jeun Young Park, 55 Naugler Ave.,
Marlboro, Mass. 01752

Continuation-in-part of abandoned design application Ser. No. 229,625, Feb. 25, 1972. This application Mar. 20, 1973, Ser. No. 346,572

Term of patent 3½ years

Int. Cl. D26—05

U.S. Cl. D48—20 R

FIG. 1

FIG. 2

FIG. 3

FIG. 4

FIG. 5

FIG. 6

FIG. 1 is a view in front perspective of a lamp showing my new design,

FIG. 2 is a view in rear perspective thereof,

FIG. 3 is a view in front elevation thereof,

FIG. 4 is a view in rear elevation thereof,

FIG. 5 is a view in side elevation thereof,

FIG. 6 is a top plan view thereof.

The base of the lamp is stippled to indicate contrast with the globe.

This is a continuation-in-part of design application D. 229,625 filed Feb. 25, 1972 and now abandoned.

I claim:

The ornamental design for a lamp, as shown and described.
